United States Patent Office

Des. 188,628
Patented Aug. 16, 1960

188,628

BOTTLE

Walter T. Heintze, Lewisboro, N.Y., assignor to Bristol-
Myers Company, New York, N.Y., a corporation of Delaware

Filed Dec. 11, 1958, Ser. No. 53,734

Term of patent 14 years

(Cl. D58—6)

FIG.1

I claim:

The ornamental design for a bottle, as shown and described.
